INVENTOR
JOHN C. TUCKER

BY *Fetherstonhaugh, Inc.*
ATNS.

UNITED STATES PATENT OFFICE.

JOHN CLIFFORD TUCKER, OF VETERAN, ALBERTA, CANADA.

CAN STOPPER.

Application filed June 2, 1923. Serial No. 642,998.

To all whom it may concern:

Be it known that I, JOHN CLIFFORD TUCKER, a subject of the King of Great Britain, residing at Veteran, in the Province of Alberta and Dominion of Canada, have invented certain new and useful Improvements in Can Stoppers, of which the following is a specification.

This invention relates to can stoppers and has for its objects to provide stoppers especially adapted to be used on cans provided with a spout, to provide removable caps designed to normally close the spout and can opening; to provide means to resiliently connect the two caps together, to provide means whereby the caps on being removed are engaged on the flange of the can opening of the wall of the spout.

Further objects are to provide stoppers for a can which are not adapted to be separated from the can but only displaced in order to clear the opening that they normally close.

Still further objects are to provide an improved can stopper which is simple in construction, not liable to go out of repair, and generally to adapt the several parts to better perform the functions required of them.

Still further objects are to provide an improved can stopper such as described in the following specification illustrated in the accompanying drawings and set forth in the appended claims.

Referring to the drawings:

Figure 1 is a side elevation of a top part of a can provided with the improved stopper.

Figure 2 is a longitudinal section through the same, and

Figure 3 is an enlarged sectional detail taken through the flanged opening of the can.

In the drawings, in which like characters of reference indicate corresponding parts in all the figures,

A represents a can of usual construction provided with a spout 10 and a flanged opening 11. A strip of sheet metal 12 is provided which extends within the spout 10 and has its end 13 beaded over the flange 11 of the can, while its opposite end is beaded as at 14 over the spout 10. The purpose of this strip is to provide a smooth contact for the spring and prevent the same catching on the angle formed by the connection of

the spout with the top of the can. The flanged opening 11 is provided with a cap 15 having its flange in frictional engagement with the flange 11 of the opening and the cap 15 is provided with a gripping ring 16 having a stem 17 extending through the cap and to which is connected a hook member 18 which is best illustrated in Figure 3 of the drawings. The hook 18 is preferably formed of stout steel wire and is provided intermediate of its length with two offsets 19 and 20 designed to form a kink which engages the flange 11 of the opening of the can when the cap is displaced in order to clear the opening.

A gasket or leak tight disc 21 is provided in the cap 15 which when the cap is in normal position lies between the cap and the top of the flange 11 in order to form a leak proof joint. The spout 10 is also normally closed by a similar cap 22 which is also provided with a ring 23 formed with a stem 24 extending through the cap and engaged by a hook 25 exactly similar to the hook 18 previously described. The cap 22 is also provided with a gasket or leak proof disc 26 which normally rests in the bottom of the cap engaging the edge of the spout 10. The hooks 18 and 25 are joined by a resilient element 27 which extends along the sheet metal strip 12, as clearly shown in Figure 2 of the drawings.

When the substance contained in the can equipped with this improved stopper is to be poured out, the ring 23 of the cap 22 is engaged by the fingers and the cap is pulled out until the kink in the hook 25 becomes adjacent the wall of the spout 10 when the ring 23 is released in order to allow the hook to engage the wall of the spout which is retaining the cap in a displaced position just clear of the opening in the spout and this allows the liquid to be poured out from the can.

The cap 22 may be replaced by a similar disengaging hook 25 from the wall of the spout and allowing the spring 27 to retract the cap into position above the end of the spout 10 and the spring 27 will hold the cap 22 tight enough on the spout 10 in order to insure a leak proof joint.

If the can A is to be filled with oil or other substance, the cap 15 is removed in a similar manner to the cap 22 by the ring 16 being engaged and pulled out until the offset hook 18 is brought in a position to be engaged by the flange 11 of the open-

- ing, in which position the cap 15 is located owing to the pulling action of the resilient member 27. The cap 15 is replaced on the flange 11 of the opening by disengaging the hook 18 from the flange and allowing the resilient element 27 to retract and pull the cap 15 back in engagement on to the flange 11 of the opening, thus providing a leak proof closure for the can opening.
- 10 The gaskets 21 and 26 of the caps may be formed of rubber or cork or, in fact, any suitable material which will be found to provide the better joint between the cap and the flanges of the opening.
- 15 As many changes could be made in the above construction and many widely different embodiments of my invention within the scope of the claims, constructed without departing from the spirit or scope thereof, it is intended that all matter contained in the accompanying specification and drawings shall be interpreted as illustrative and not in a limiting sense.
- What I claim as my invention is:
- 20 1. A can stopper comprising in combination with a can having a flanged opening, and a spout, a removable cap for the spout, gripping means having stems extending through the respective caps, means engaging
- 25 the stems whereby the caps may be secured in open position, and a resilient element joining the said means.
2. A can stopper comprising in combination with a can having a flanged opening and a spout, a removable cap for the flanged opening of the can, a removable cap for the spout, gripping means having stems extending through the respective caps, a hook on each stem designed to engage the flange of the cap opening and the spout, whereby the caps may be secured in open position, and a resilient element joining the hooks.
3. A can stopper comprising in combination with a can having a flanged opening and a spout, a sheet metal strip extending within the spout and secured to the flanges of the opening and spout, a removable cap for the flanged opening, a removable cap for the spout, a grip ring on each cap, hook members carried by the caps and a resilient element extending along the metallic strip and connecting the two hooks.

In witness whereof I have hereunto set my hand in the presence of two witnesses.

JOHN CLIFFORD TUCKER.

Witnesses:

JAMES HOWARD BALLENTINE,
FREDERICK MASON.
